UNITED STATES PATENT OFFICE

90,627

DESIGN FOR AN AIRPLANE

Lessiter C. Milburn, Towson, Md., assignor to The
Glenn L. Martin Company, Baltimore, Md.

Application May 13, 1933. Serial No. 48,112

Term of patent 14 years

To all whom it may concern:

Be it known that I, LESSITER C. MILBURN, a citizen of the United States, residing at Towson, in the county of Baltimore and State of Maryland, have invented a new, original, and ornamental Design for Airplanes, of which the following is a specification, reference being had to the accompanying drawings, forming part thereof.

Fig. 1 is a perspective view of the subject airplane in flight, the gun being omitted.

Fig. 2 is a perspective view differing from Figure 1 in angularity.

Fig. 3 is a front elevation of the airplane shown in either figure when the landing wheels are extended for ground engagement.

Fig. 4 is a side elevation, and

Fig. 5 is a side elevation of the subject airplane when the landing wheels are retracted as shown in Figures 2 and 5.

I claim:

The ornamental design for an airplane substantially as shown and described.

LESSITER C. MILBURN.
